UNITED STATES PATENT OFFICE.

WILLARD A. SMITH, OF MELROSE, MASSACHUSETTS, ASSIGNOR, BY MESNE ASSIGNMENTS, TO UNITED SHOE MACHINERY COMPANY, OF PATERSON, NEW JERSEY, A CORPORATION OF NEW JERSEY.

FASTENING-MACHINE.

962,105.

Specification of Letters Patent. Patented June 21, 1910.

Application filed January 16, 1906. Serial No. 296,288.

To all whom it may concern:

Be it known that I, WILLARD A. SMITH, of Melrose, in the county of Middlesex and State of Massachusetts, have invented certain new and useful Improvements in Fastening-Machines, of which the following is a specification.

The present invention relates to machines for lacing together the eyeleted quarters of shoe uppers preparatory to placing them on a last for the lasting and other subsequent operations, in order that the edges of the lacing slit shall be held at the proper distance apart and the upper be permitted to be flattened out and properly fitted to the last during the lasting operation.

The invention is intended primarily as an improvement in shoe upper lacing machines which comprise a plurality of needles arranged to pass a series of loops of lacing cord through the eyelet holes of an upper, and particularly as an improvement on the shoe upper lacing machine disclosed in applicant's prior Patent No. 779,008 dated Jan. 3, 1905. In its broader aspects, however, the present invention is applicable to other forms of shoe upper lacing machines, and it is to be understood that except as specifically defined in the claims the various features of the present invention are not limited to a machine having its various parts constructed and arranged as in the machine of the patent above referred to, nor are they limited to the specific construction and arrangement of parts hereinafter described as constituting the preferred embodiment of the invention.

The object of the present invention is to provide a shoe upper lacing machine having its various parts constructed and arranged in an improved and simplified manner, and having an improved mode of operation whereby the machine is adapted to perform the operation of lacing a shoe upper with certainty and at a greater rate of speed and in a more reliable and satisfactory manner than shoe upper lacing machines that have heretofore been devised.

With this object in view the various features of the present invention contemplate the provision in a shoe upper lacing machine of an improved needle for passing a loop of lacing cord through the eyelet holes of an upper without liability of the eyelets or the

upper catching on the needle; the provision of a thread finger arranged to pull cord from the supply to be used in forming the loops which are inserted through the eyelet holes of the upper whereby excessive rendering of the cord through the eyes, or slots of the needle or needles is prevented; the provision of improved means for adjusting the needles of a multiple needle machine to adapt the machine for operation upon uppers having the eyelets differently spaced; the provision of improved means for varying the amount of slack formed in the lacing to permit different styles of upper to be flattened out and positioned properly on the last; the provision of improved work guards for preventing the upper being injured by the lacing instrumentalities during the operation of the machine; the provision of an improved construction and arrangement of the clamps, or grippers, for holding the ends of the lacing cord, and improved mechanism for operating said grippers, or clamps; the provision of an improved means for severing the lacing from the supply of lacing cord; the provision of an improved knot tying mechanism; the provision of a device in connection with the knot tying mechanism for tightening the knot; the provision of a work adjuster or holder for positioning the work properly during the lacing operation, and the provision in connection with said work adjuster and holder of a stop mechanism for throwing the machine into and out of operation so constructed and arranged that the work is properly adjusted before the lacing instrumentalities are put in operation.

The various features of the invention above referred to will be clearly understood from an inspection of the accompanying drawings, in which is illustrated a shoe upper lacing machine embodying the same in their preferred form. This machine in addition to embodying the features of invention above referred to also embodies certain novel features of construction and arrangement of parts hereinafter described and claimed, the advantages of which will be obvious to those skilled in the art from the following description.

Referring to the drawings Figure 1 is a plan view of a shoe upper lacing machine embodying the various features of the pres-

ent invention in their preferred form. Fig. 2 is a view in end elevation of the machine illustrated in Fig. 1. Fig. 3 is a view in front elevation on an enlarged scale, of a portion of the machine. Fig. 4 is a detail plan view illustrating the looper needles and looper fingers, and the mechanism by which they are supported and actuated. Fig. 5 is a view in side elevation of the mechanism illustrated in Fig. 4, the view being taken on the section line 5—5 of Fig. 1. Fig. 6 is a view similar to Fig. 5 but showing only the looper fingers and the mechanism for supporting and actuating the same. Fig. 7 is a cross-sectional view on the line 7—7 of Fig. 5. Fig. 8 is a plan view of a portion of the mechanisms illustrated in Fig. 4 on a somewhat larger scale. Fig. 9 is a detail sectional view taken on the line 9—9 of Fig. 8. Fig. 10 is a detail cross-sectional view taken on the line 10—10 of Fig. 9 looking in the direction of the arrow. Fig. 11 is a cross-sectional detail view taken on the line 11—11 of Fig. 9, looking in the direction of the arrow. Fig. 12 is a detail perspective view of a bar forming a portion of the needle rotating mechanism. Fig. 13 is a detail view in front elevation of a portion of the machine illustrating the feeder needle carrier and the tension device for the lacing cord. Fig. 14 is a detail cross-sectional view taken on the line 14—14 of Fig. 13. Fig. 15 is a detail sectional view on a larger scale than Figs. 13 and 14, taken on the line 15—15 of Fig. 14. Fig. 16 is a view in elevation of the end of the machine opposite to that shown in Fig. 2, certain of the parts which would appear in this figure being omitted to avoid confusing the drawing. Fig. 17 is a detail plan view of the knot tying mechanism. Fig. 18 is a view in side elevation of the mechanism illustrated in Fig. 17. Fig. 19 is a vertical sectional view on line 19—19 of Fig. 18, showing also a portion of the machine frame adjacent to the knot tying mechanism with a work guard and the cord clamps, or grippers, mounted thereon. Fig. 20 is a vertical sectional view of the knot tying mechanism taken in a plane at right angles to that of Fig. 19. Fig. 21 is a vertical sectional view of the knot tying mechanism taken on the same plane as Fig. 19, but showing the gripping jaws open. Figs. 22, 23 and 24 are detail cross-sectional views taken respectively on the lines 22—22, 23—23 and 24—24 of Fig. 20. Fig. 25 is a detail plan view illustrating the lacing cord clamps, or grippers, and their actuating mechanism. Fig. 26 is a view in side elevation of the mechanism illustrated in Fig. 25. Fig. 27 is a detail plan view illustrating the thread finger and the knot tightener and the mechanism by which these parts are actuated. Fig. 28 is a view in side elevation of the mechanism illustrated in Fig. 27, with a portion of the

machine frame shown in section. The plane of this figure on Fig. 1 is indicated by the line 28—28. Figs. 29 to 33 inclusive are detail plan views illustrating particularly the positions which the looper needles, looper fingers and cord feeding needle occupy at different stages in the operation of the machine. Figs. 34 to 39 inclusive are detail views in front elevation illustrating the operation of the knot tying mechanism, Fig. 39 also illustrating the action of the thread finger in placing the lacing cord between the jaws of the knot tying mechanism. Fig. 40 is a view in side elevation of the parts illustrated in Fig. 39. Figs. 41 and 42 are views in front and side elevation illustrating the action of the knot tightener in tightening the knot. Figs. 43 and 44 are detail perspective views of the gripping jaws of the knot tying mechanism. Fig. 45 is a view in side elevation of a portion of the machine with several of the parts shown in section, illustrating the work adjusting mechanism and the stop mechanism. Figs. 46 and 47 are detail views in side elevation but looking in opposite directions of the stop mechanism. Fig. 48 is a detail view illustrating a portion of a shoe upper as it appears after having been laced by the machine. Fig. 49 is a detail view illustrating three positions which the looper needle carrier occupies at different times during the operation of the machine. Fig. 50 is a detail plan view illustrating a modified construction by means of which the looper fingers can be adjusted simultaneously. Fig. 51 is a cross-sectional view taken on the line 51—51 of Fig. 50, looking in the direction of the arrow. Fig. 52 is a detail view illustrating the guide for the feeder needle carrier in cross-section and two of the work guides in side elevation. Fig. 53 is a detail view in side elevation of a modified construction for adjusting the looper needles longitudinally. Fig. 54 is a view in front elevation of the mechanism illustrated in Fig. 53.

The machine illustrated in the drawings, like the machine disclosed in the patent above referred to, is adapted to pass a series of loops formed in a lacing cord through the eyelet holes of an upper, and thereafter to pass a portion of the lacing cord through the loops, sever the lacing from the supply and tie the ends of the lacing together. The machine comprises a plurality of needles, equal in number to the number of pairs of eyelet holes which it is desired to lace, a plurality of looper fingers coöoperating with the needles to form the lacing cord into loops and retain the loops in position until the shoe upper is placed on the needles, a cord feeding needle to place the cord in position to be engaged by the needles and looper fingers and to pass a portion of the cord through the loops after they have been

inserted in the eyelet holes of the upper, cord clamps or grippers to hold the ends of the lacing, a cutter to sever the lacing from the supply, and a knot tying mechanism to tie the ends of the lacing together. To enable the needles to pass the loops of lacing cord through the eyelet holes of the upper without difficulty, the eye or slot of each needle which receives the lacing cord is located a short distance from the end of the needle and opens at one side of the needle, so that no projection is formed in the needle which can engage the eyelet or upper. The lacing cord is placed by the cord feeding needle at one side of the looper needles, and to cause the cord to be engaged by the needles a relative lateral movement of the cord and needles is produced by moving the carrier in which the needles are mounted. The needles are mounted in their carrier so as to be adjustable with reference to each other to suit the spacing of the eyelets in the upper to be operated upon and to permit the adjustment of the needles to be made easily and quickly means are provided whereby the required adjustment of all of the needles is made simultaneously. To form the lacing cord into loops the needles and looper fingers are moved longitudinally in opposite directions. The length of cord taken up by the loops remains in the lacing and provides a sufficient amount of slack in the lacing to permit the upper to be flattened out and properly fitted to the last. It will be evident that the amount of slack produced in the lacing can be varied by varying the length of cord taken up in forming the loops and in the machine illustrated in the drawings this is accomplished by adjusting the looper fingers longitudinally, means being provided whereby all the looper fingers can be adjusted simultaneously.

Two cord clamps or grippers are provided located at one side of the looper needles and looper fingers, one gripper being actuated to grasp and hold the free end of the lacing cord, and the other gripper being actuated to grasp the end of that portion of the cord which is passed through the loops of the lacing. To enable these grippers to grasp the cord with certainty, they are arranged to operate in close proximity to the path of the cord feeding needle, and at substantially the same distance therefrom. By this arrangement of the grippers and cord feeding needle the cord is presented accurately to one or the other of the grippers at each reciprocation of the needle.

The means for severing the lacing from the supply of lacing cord consists of a cutting blade mounted upon one of the cord grippers across the edge of which the cord is drawn during the backward movement of the cord feeding needle after the lacing of the upper has been completed. A sufficient

tension is put upon the cord to cause the cutter to sever the lacing by means of an intermittently acting tension device which engages the cord during a portion of the backward movement of the cord feeding needle.

The knot tying mechanism is located at one side of the looper needles and looper fingers between the needles and the cord grippers. This knot tying mechanism is adapted to tie the ends of the lacing together in a certain and reliable manner, and permits the laced upper to be dropped from the machine without any liability of interfering with the subsequent operations of the lacing devices. The novel features of this knotting mechanism consist in certain constructions and arrangements of its parts which will be hereinafter described.

In addition to the parts above referred to, the machine illustrated in the drawings is also provided with a knot tightener consisting of a finger which acts upon the lacing, while still held by the knot tying mechanism, to tighten the knot, and with a thread finger which acts upon the cord between the looper needles and the cord grippers prior to the formation of the loops, and pulls out a length of cord which is used in forming the loops so that the cord for the loops is supplied from both sides of the needles and an excessive rendering of the cord through the eyes or slots of the needles is prevented.

To prevent the work from projecting into the path of movement of the cord feeding needle, or from assuming any position which would interfere with the operation of the machine work guards are provided on each side of the looper needles, and one of these work guards is adjustable toward and from the needles so that it may be brought into desired position with relation to the needles when the needles are adjusted.

The machine is also provided with a work adjuster for forcing the upper into position on the looper needles, and with a stop mechanism for throwing the machine into and out of operation. The work adjuster consists of a plate mounted to move from a position at one side of the needles across the ends of the needles and then longitudinally of the needles a sufficient distance to force the upper into the desired position on the needles. The work adjuster also serves as a guard to prevent injury to the hands of the operator by the lacing devices, and particularly of the cord feeding needle, since the hand of the operator cannot remain in the path of movement of the cord feeding needle during the movement of the work adjusting plate across the ends of the looper needles. The work adjusting plate is actuated through connections which control the operation of the stop mechanism, and these connections are so arranged that the work

adjusting plate is brought into operation before the machine is thrown into operation. The correct positioning of the work is thus insured, and also all danger of injury to the operator is avoided.

Referring now to the drawings, and particularly to Figs. 2, 4 and 5, the numeral 10 designates a frame including separated side members 11, 11, in which is mounted a shaft 12 carrying a yoke 13, to which are pivoted arms 14, 14 of the needle carrier 15. Articulated to the under side of the forward end of the carrier is a link 16, in which may be included a turn-buckle 17, allowing an adjustment of the stroke of the carrier, this link being pivoted at its opposite end to an angle lever 18, turning about a shaft 19 extending between the sides of the frame. In the end of the lever 18 is secured a stud 20 carrying a cam roll 20^a, arranged in a cam path 21 formed in the face of a disk 22 fixed to the shaft 22^a. The cam path imparts to the lever 18 and to the forward end of the carrier an angular movement which is most clearly shown in Fig. 49, there being a maximum downward position indicated at X, in which the needles are in position to receive the work and to have the work stripped therefrom, an extreme upward position indicated at Y, in which the eyes or slots of the needles receive the lacing cord, and an intermediate or mean position indicated at Z, in which the needles are in position to permit the passage of the cord feeding needle 35 through the loops of the lacing. During the operation of the machine the needle carrier also assumes a fourth position slightly below that indicated at Z, to allow the cord feeding needle to pass over and in close proximity to the needles in feeding the lacing cord to the needles preparatory to the formation of the loops. Across the outer end of this carrier is a front plate 23 (Figs. 3, 8 to 11, inclusive) forming a space in which are situated square blocks or holders 24 for the needle spindles 31 that carry the needles 25. Five of these needles 25 are here shown, but it will be obvious that any desired number may be employed according to how many eyelet openings are to be laced. Each needle has at one side, near its outer extremity, a slot or eye 26 which extends longitudinally of the needle and opens at one side in a throat 27, which is formed by cutting away the wall of the needle at this point. Below each slot 26 is a groove 28 that lies about 90° from the slot with reference to the circumference of the needle, these grooves 28 being provided to facilitate the passage of the cord carrying needle through the loops of the lacing. Each needle is secured in its spindle by a set-screw 29, which secures the needle in the tubular socket 30 of the spindle 31. The inner end of the spindles 31 projects into a chamber 32 within the car-

rier. At the other end each spindle is formed with a shoulder 33 that receives the set-screw 29 and prevents the inward movement of the spindle. A collar 34 secured to the end of each spindle 31, and located in the chamber 32, prevents the outward movement of the spindle. From this collar projects a crank 35, having a crank-pin 36 by which each spindle may be rotated by mechanism, which will be hereinafter described. The block or holder 24 at the right of the plate, as seen in Fig. 3, is fixed, while the remainder may be adjusted with relation to one another to provide for the different positions of the needles, due to different spacings of eyelet holes in the upper. In the space at the rear of the front plate depend from each holder 24, pairs of separated arms or extensions 37, 37, connecting respectively to those adjacent to them at each side by links 38. The upper ends of these links are pivoted to the arms 37 at 39, while the lower ends carry pins 39^b, operating in slots 39^a in the ends of the arms 37, Fig. 11. These links are articulated to one another at intermediate points 40 so that a lazy-tongs system is formed by which a proportionate movement is imparted to all the holders. To the outside holder arm at the left is pivoted a link 41 operating through a slot in the front plate, and being joined at its opposite end to an adjusting lever 42, fulcrumed upon said plate. In this lever is a quadrant slot 43, having extended through it a binding-screw 44, allowing the position of the lever to be adjusted. It will be seen that by this mechanism all the holders, spindles and needles may be simultaneously moved laterally, and the proper spaces between them secured and maintained. The needles 25 are moved longitudinally, to enable them to effect their share in the looping operation, by a reciprocation of the carrier through an oscillation of the yoke 13 that is provided with a cam roll 45, entering a cam path 46, in a disk 47, (Fig. 5) fixed to the shaft 22^a.

The looper fingers which coöperate with the needles in forming the lacing cord into loops are mounted and actuated as follows:—In the carrier 15 (Fig. 7) is formed a dove-tailed groove, or way 48 to receive and permit of the reciprocation of a complementary tongue 49 (Figs. 4 to 9 inclusive) formed on the bottom of a support 49^a, which is moved longitudinally of the carrier, to actuate the looper fingers, by a connecting rod 50 that is pivoted at one end to the support 49^a, and at its opposite end to the free end of a lever 12^a pivoted on the shaft 12. The arm 12^a carries a cam roll 51 arranged in a cam path 52 of a cam disk 53 fast upon the shaft 22^a. At the forward end of the carrier are secured plates 55, which serve as guides for the front end of the movable plate 56 upon which the looper fingers

are mounted. The plate 56 carries a perforated lug 57 through the opening in which extends a screw 58 fixed in a post 59, which projects from the support 49^a. Nuts 60 operating upon the screw 58 at each side of the lug 57 permit the plate 56 to be adjusted with relation to the support 49^a to vary the position of the looper fingers with relation to the needles, and thus vary the 10 length of the loops formed in the lacing cord and the amount of slack left in the completed lacing. The plate 56 is guided in its movement of adjustment by screws 61 which extend through longitudinal slots 62 in the 15 plate 56 and are threaded in the support 49^a. In the outer end of the plate 53 is a slot 63 receiving projections 64 on looper finger holders 65, and which also have projections 67 rising outside of the end of the plate 56. 20 The projections 64 are adapted to receive screws 68, the heads of which contact with the clamping plate 69, serving to fix the holders in position upon the plate 56. Through the projections 67 are set-screws 70, 25 the lower ends of which contact with looper fingers 71, which are mounted in bores in the looper finger holders 65. The outer end of each finger 71 is bent downward, and provided with a roll 72, arranged between adjustment 30 cent needles 25, and reaching to a point below them.

The needle spindles 31 are rotated at certain times during the operation of the machine, and to this end their crank pins 36 enter a longitudinal slot 36^a in an actuating bar 73 (Figs. 9, 10 and 12) which has at each end a recess 74 adapted to receive the spherical extremities of angle-levers 76, fulcrumed upon a lug 77, rising from the carrier 15, within the chamber 32. (Fig. 9). The opposite and upper ends 78 of these levers extend in the path of the opposed lugs 79, 79, formed on plates 80 that are secured by screws 81^a to the support 49^a at each side 35 of the plate 56. As the support 49^a and the carrier 15 are moved relative to one another, the end 78 of each bell-crank 76 contacts first with one and then with the opposite of these lugs 79, 79, and are swung thereby, 40 raising and lowering the bar 73, and simultaneously rotating the spindles 31, through an arc of substantially 90°, so that the throats 27 of the needles 25 lie, first, in alignment with one another in a horizontal plane, 45 and then lie parallel to one another in vertical planes.

The cord feeding needle is indicated at 86 and is secured by means of a set screw 87 in an arm 85 depending from a carrier 84. 50 The carrier 84 is mounted to reciprocate in a guide-way 83 formed in a guide 82, supported by arms 82^a secured to the frame of the machine. The extremity of the cord feeding needle toward the looper mechanism 55 is inclined at its upper side at 88, and in

proximity to this incline 88 the needle is formed with an eye 89 through which the lacing cord L passes. The needle 86 is so located with relation to the angular movement of the carrier 15 that when the latter is in a position just below its mean position Z (see Fig. 49) the needle will lie in a line just above the throats 27 of the needles 25. Journaled upon the guide 82, at its inner side, is a shaft having fixed upon it a gear 95, meshing with a rack 96 carried by the inner side of the carrier 84. The shaft 94 also has fast upon it a smaller gear 97, which meshes with a segmental gear 98, formed upon the end of a lever 99, fulcrumed upon the frame-work of the machine. At its opposite extremity this lever 99 has a cam roll 99^a arranged in a cam path 100 upon the periphery of a cylinder cam 101 fast on the shaft 22^a. By this mechanism a reciprocation of 85 the needle 86 is secured from one extreme, as illustrated in Fig. 1, to an opposite extreme, somewhat beyond the position shown in Fig. 32.

The work guards by which the shoe upper 90 is prevented from projecting into the path of the cord feeding needle or assuming a position which would interfere with the lacing operation, are indicated at 90, 91 and 176, the guards 90 and 91 being located at the 95 left of the looper needles and the guard 176 at the right, as viewed in Fig. 3. The guards 90 and 91 consist of plates secured to the guide 82 and projecting downwardly therefrom, the guard 90 being stationary 100 and the guard 91 being adjustably mounted upon the guard 90 in order that it may extend close to the looper needles in all adjustments of the needles. At the edges adjacent the looper needles, the guards 90 and 91 are 105 provided with forwardly projecting flanges and at their lower ends are provided with eyes 90^a through which the work feeding needle 86 passes. The guard 176 consists of an arm secured to the frame of the machine and projecting downwardly into a position to coöperate with the knot tightener of the knot tying mechanism as will be hereinafter described. When the work is inserted in the machine, it passes beneath or 110 inside of the guards 90, 91 and 176 and thus the work is held out of the path of the cord feeding needle and is also prevented from interfering with the action of the knot tying mechanism. 115

Referring now to Figs. 1, 2, 25, 26 and 34 to 39, inclusive, at the side of the looper mechanism opposite the shuttle is a head 102 on the frame work, and in this head are mounted to slide vertically the cord clamps 125 or grippers, which in the form shown are bars 103, 104, having reduced ends adapted to enter grooves 105 in a plate 106 projecting outwardly from the lower portion of the head 102. In recesses in the upper side of 130

these gripping bars (Fig. 26) extend the rounded ends of levers 107, fulcrumed upon the frame-work, and having cam faces 108 coöperating with cam faces 109, carried by one extremity of an arm 110 which projects from the sleeve 111, loosely mounted on a stud 112. The sleeve 111 also has an arm 113 carrying a cam roll 113^a arranged in a cam path 114 in one side of a disk 115 fixed to the shaft 22^a. Springs 116 act to maintain the cam faces 108, 109 in engagement. The grippers may be adjusted to exert the desired amount of pressure on the cord by means of adjustable sections 116^a formed on the levers 107 which sections are adjusted by means of adjusting screws 117 and 118. The grippers are arranged just at one side and at substantially equal distances from the path of the needle 86, and their lower ends project forwardly. Fixed to the gripper which is farthest from the source of cord supplied is a blade or cutter 119, having a sharp edge 120 over which the cord is drawn during the backward movement of the needle 86 after the cord has been passed through the loops of the lacing and clamped by the gripper. As the needle draws the cord over this cutting edge, tension is applied to the cord between the needle and the source of supply by a device mounted on the needle carrier, so that the cord is drawn against the temporarily immovable blade to sever the lacing. To this end the cord passes through eyes 121^a in spaced lugs 121, 121, on the arm 85 of the needle carrier. (See Figs. 1, 13, 14, 15 and 16.) Into the space between the lugs 121, 121, moves a tension arm or lever 122, fulcrumed upon the needle carrier 84, and having at its upper extremity a roller 123, which contacts with the outer face of a cam bar 124, supported upon screws 125 from an actuating lever 126, fulcrumed at 126^a to a lug on the rear of the needle carrier guide 82. (See Fig. 14.) Pivoted to the lever 126 is a link 127 (Fig. 16) articulated at its opposite end to an angle lever 128, which has a cam face 129, for coöperation with a cam roll 130 fixed to the adjacent face of the cam cylinder 101. The contact of the cam roll 130 with the cam face 129 moves the cam bar downwardly into the path of the tension-arm roll as it travels outwardly with the needle. This throws the end 122^a of the lever 122 between the lugs 121, 121, causing the cord to rest between it and the depression 131 in the opposite face of the carrier. The tension arm 122 is preferably positively released by the contact of the roll 123 with the under-cut face 131^a of a projection from the guide 82. To vary the tension upon the cord to accommodate the machine to the use of various sizes the cam bar is movable between the heads of the screws 125 and the arm 126, and with the inner side of the bar

contacts a roll 132 carried by an adjusting arm 133 swinging about the same point as the tension arm. Through the adjusting arm is threaded a screw-bolt 134, which by its contact with block 84 forces the adjusting roll against the tension plate 124, and this latter member outwardly toward the screw-heads, thus increasing the throw of the tension lever. 70

Figs. 29 to 33 illustrate the lacing operation. The carrier 15 being in a position just below the position indicated at Z, Fig. 49, the needle 86 carrying the cord passes above the throats of the looper needles and just inside the depending portions of the looper fingers, these parts at such time occupying the positions shown in Fig. 29. Beyond the knotting mechanism the cord is grasped by the gripper 103, which has risen and then descends upon the cord. The needle 86 then retreats, the carrier 15 rises to the position indicated at Y, Fig. 49, to place the cord in the eyes of the looper needles, and the needles partially advance to set the cord in the eyes of the needles and at substantially the same time the looper fingers are partially retracted. The carrier 15 now drops to its lowest position and the movement of the looper needles and the looper fingers is continued to form the loops, while at the same time the looper needles rotate 90° upon their axes to bring the legs of the loops in position to permit passage of the needle 86. A shoe upper S. is now placed upon the needles by the operator, (Fig. 31), and the needle 100 carrier 15 rises to the intermediate position shown at Z, (Fig. 49,) whereupon the needle 86 advances through the loops in the grooves 28, carrying the cord to the second gripper 104, which grasps it. Then as the needle retreats the cord is drawn across the cutting edge of the knife 120, and after the said needle has reached a certain point in its backward movement the tension 122^a, (Fig. 15) is applied, as has been described. This 110 holds the cord so that the further motion of the needle draws the cord against the knife 120 and severs the lacing. After the needle 86 has caused the cutting of the cord, and has moved back far enough to clear the needles and looper fingers, the carrier 15 returns to its lowest position and the needles and looper fingers move to the position shown in Fig. 33, throwing off the work and leaving it hanging from the gripper members and the knot-tying members. 115 120

Situated between the looper needles and the cord grippers is the knot-tying mechanism which will now be described, reference being had to Figs. 1, 2, 17 to 24, and 34 to 125 44. Mounted in the head 102 is a sleeve or rotatable section 135 which has on its upper portion a pinion 136, (Fig. 18.) With this pinion meshes a segmental gear 137 formed upon a lever 138, fulcrumed in the frame 130

and having a cam roll 139 arranged in a cam path 140 in the periphery of the cylinder 150^a. Within the sleeve 135 are two longitudinally movable sections or gripping members 141, 142 (Figs. 19 and 43) which, as shown, are semi-cylindrical. The member 141 is formed at its lower end with a jaw 143, arranged below a roughened face or jaw 144 of the coöperating member 142. A collar 145^a (Figs. 17 to 21) is secured to the member 142 above the sleeve 135 by a screw 142^a, and a like collar 145 is secured to the member 141 above the collar 145^a. The collar 145^a is grooved to receive a ring 146^a, while the collar 145 is in like manner grooved to receive a ring 146. 149 represents a short shaft carried by the framework of the machine, and upon this shaft is loosely mounted two sleeves 147^a, 148^a. The sleeve 147^a is formed with a lever 147, provided on its end with a fork 147^b that is connected to the ring 146 by screws 149. The sleeve 148^a in like manner is formed with a lever 148 provided at its end with a fork 148^b connected to the ring 146^a by screws 149^a. The sleeve 147^a is further formed with a lever 147^c that carries a cam roll 150 arranged in a cam path 151 in one end of the cylinder 150^a. The sleeve 148^a is formed with a lever 150^c carrying a cam roll 150^d that lies in a cam path 150^e at the end of the cylinder 150^a opposite the cam path 151. The sections 141, 142 are recessed to provide between them openings 152, 153, through the former of which and the walls of the sleeve 135 extends a key 154, (Fig. 20) that compels these parts to rotate in unison while permitting longitudinal movement of the members 141, 142. In the opening 153 is a pin 155 upon which is pivoted a retaining member or latch 156, the upper end portion 157 of which extends outside of the opening below the sleeve 135, while the opposite end may enter a recess 158 formed in the section 142 adjacent to its roughened surface 144. This latch 156 is preferably looped or bent outwardly from the members 141, 142 to furnish a space 159, which may lie in the path of the cord feeding needle in one angular position of the tying mechanism. In the curved wall of the member 142, near its lower end, is shown a groove 160 (Figs. 19, 43) serving to retain the cord against premature displacement from the tying mechanism, and being downwardly inclined to compensate for the upward movement of the sections 141, 142. The member 141 (Fig. 44) at one side of the jaw has an inclined face 161, which directs the cord downwardly below the latch. Depending from the sleeve 135 (Figs. 34 to 40) and partially surrounding the gripping members of the tying mechanism, is a half sleeve 162, the length of which is such that the lower extremity will co-act with the cord to strip it from the longitudinal movable sections 141, 142, as they travel upwardly. The lower end of the sleeve 135 strikes the end 157 of the latch upon the upward movement of the sections 141, 142, swinging the looped portion outwardly to release the cord. The lower portion of the half sleeve 162 has a face 164 with which the end 157 of the latch 156 contacts upon the reverse movement of the parts in the downward movement of members 141, 142 to positively return the latch to its initial position.

Referring to Figs. 2, 27, 28 and 40, a thread arm 165 is arranged between the tying mechanism and gripping members and formed with a curved portion to engage the cord. This arm depends from a bar 166 mounted to slide in the frame, and is reciprocated by a link 167 connected to a bell-crank 168 that at its inner end coöperates with cam projections 169, 169^a on the periphery of the cam 53. (Figs. 27, 28.) This thread arm, after the first gripper takes the thread, and the needle 86 begins to recede, moves rearwardly across the path of the needle to take up cord from the supply. After the needle has completed its backward stroke, and the fingers move rearwardly to form the loops, the thread arm moves forward to give up cord so that the cord in the loops will come from both the thread arm and the eye of the needle, thus preventing undue rendering of the thread or cord through the eyes of the looper needles. Thereafter the actuating mechanism effects an appropriately timed movement of the thread arm 165 to draw the cord positively between the jaws of the tying mechanism. After the knot is tied the thread arm moves to draw the two cord ends out of the cord grippers. The thread arm thus serves three purposes; first, it takes up the cord before the loops are formed, and as the loops are being formed pays out such surplus cord, so that the cord is not all drawn from the source of supply to form the loops, thus preventing rendering and giving a more even strain to the cord, on the needles; second, the thread arm acts to draw the cord between the jaws of the knotter, (Figs. 38, 39;) third, the thread arm acts to draw the ends of the cord out of the cord gripper after the completion of the knot.

Below the tying mechanism projects a knot tightening arm 170 (Figs. 2, 27, 28, 41 and 42) carried by a bar 171 movable through the frame below the bar 166 and operated by a link 172 joining it to an angle lever 173 which is moved by contact with a cam projection 174 of the cylinder 150^a. Springs 175 maintain the levers 173 and 168 in position to be acted upon by the cam projections. The arm 170 is reciprocated with its actuating mechanism between the tying

mechanism and the guard arm 176 fixed to the head 102. This guard arm 176 acts as a contact member against which the work is drawn by the pressure of the arm 170 upon the cord, and by resisting the movement of the work, enables the last named arm to tighten the knot which has been formed.

After the cord has been laced through the work and severed, as has been hereinbefore described, it is left hanging from gripping members 103, 104, the cord passing through the latch opening. (Fig. 34.) The sleeve 135 now begins to rotate, winding the cord about the lower portions of the members 141 and 142, successive positions, separated by angles of 90°, being shown in Figs. 35 and 36. These figures illustrate the retention of the cord by the inclined groove and its deflection by the surface 161. During this rotation both these inner members have been gradually rising, moved by the levers 147 and 148, and during the next quarter turn to the position illustrated in Fig. 37, the opening of the jaws by the arm 148 has been started. During the last quarter turn, the jaws open to substantially their full width and then the thread arm travels between the knotting mechanism and gripping mechanism to introduce the cord between said jaws. (Figs. 38 and 40.) The jaws are then closed to grip the cord, the thread arm retreats and the inner members complete their upward movement. This throws out the retaining latch by its contact with the sleeve 135, whereupon the knot is stripped from the ends of the members 141, 142, by the pressure of the sleeve portion 162, leaving the work hanging from the jaws, as is shown in Fig. 41. The movement of the arm 170 into contact with the cord below the knot draws the work against the guard arm and tightens the knot, the jaws finally separating to release the cord.

Operating in front of the looper mechanism is a work adjuster, which not only positions and retains the upper upon the needles, but also serves as a shield which prevents the operator from bringing his hands in the path of moving parts while the machine is at work. This guard comprises a main member 177, having a projection 178 extending toward the carrier 15, and being pivoted upon supporting arms 179 which are connected by a sleeve 180 (Fig. 1) fulcrumed upon a bracket 180^a. (Figs. 1, 2 and 45.) A spring 181 surrounding the pivot pin between the main member and supporting arms acts to force the guard member outwardly. The sleeve 180 is formed with two arms 182, 179, constituting a bell-crank. The arm 182 has its lower extremity lying in front of a contact collar 184 fixed to an operating rod 184^a which is connected to the arm 182 by a spring 185. Pivoted to the

inner end of the rod 184^a is a lever 184^b fast upon a shaft 187, supported upon the machine frame. A lever 186 also fast upon the shaft 187 carries a pin 188 arranged to engage a notch formed in a controlling rod 189, which extends downwardly to a treadle. 70

Rotation is imparted to the operating shaft 22^a from a driving pulley 191 (Figs. 1 and 2) formed with a hub 190, loosely mounted on the shaft 22^a. 75

193 represents a casing supported by a bracket 192^a (Fig. 1) and containing speed reducing gearing 192 connecting the hub 190 with the driving member of a clutch mechanism arranged in a casing 194, 195 secured to the shaft 22^a, which clutch mechanism may be of any preferred form or construction such for instance as is disclosed in Patent No. 767,844, dated August 16, 1904. A projection 197 on the clutch mechanism 80 contacts with the stop lever 198 that is fulcrumed on the frame and normally held in contact with the projection 197. The contact of the projection 197 with the stop lever is preferably through a movable head 90 or buffer member 200 mounted to slide in a bore in the lever 198, and having at its inner end a spring 201, which is compressed by a movement of the head, and which cushions the concussion. Rebound of the shaft 22^a 95 is prevented by a hook 202 pivoted upon the stop lever, and which may engage a projection 203 on the clutch casing 194. A spring 203^a forces the hook 202 toward the stop 203. The stop lever 198 is actuated from the controlling rod 189 through the operating lever 186 of the work guard mechanism by means of a rod 204 passing through an opening in one arm of the lever 198 and having upon each side of said arm fixed contact collars 100 205 which are so separated as to allow some play without contact. A spring 201^a extending between the frame and rod 204 normally holds the work adjuster raised with the work guard in its initial position, as 105 shown in Fig. 2. The controlling rod 189 is provided with a contact face 207 for co-operation with a face 208 upon the casing, their engagement moving the controlling rod to disengage it from the pin 188. Springs 110 209 and 210 draw the controlling rod upwardly, and toward the clutch disks, said rod resting against a surface 211 upon the frame as a fulcrum point. 115

Normally, or when the machine is at rest, 120 the elements of the stop mechanism occupy the positions illustrated in Figs. 46 and 47, the controlling rod 189, however, being shown in its lowest position, in which position it is held until the operator removes his 125 foot from the treadle. When the machine is at rest, the work guard 178 is as shown in Fig. 2. Now, the controlling rod being in its highest position, if the operator depresses the controlling rod, its contact with 130

the projection 188 first moves the operating lever of the work guard without affecting the clutch mechanism, the space between the contact collars of the rod 204 allowing this. As the operating lever swings it moves the arm 182 through the spring 185, lowering the supporting arms until they contact with stop members 212 and bring the work guard in front of the work. Then the collar 183 will contact with the work guard, drawing it inwardly until the projection 178 strikes the work, the yielding of the spring 185 permitting this additional travel of the operating rod. When this has been accomplished the upper collar 205 will have reached the stop lever. The further movement positions the work upon the needles and causes the stop lever to swing upon its fulcrum, moving the buffer head away from the projection 197 of the clutch disk and throwing the shaft 22^a into operation. Before a complete rotation of the clutch has occurred, the face 208 contacts with the face 207 upon the controlling rod, forcing the latter to one side until it is disengaged from the pin 188. Therefore, even if the foot of the operator remains on the treadle, as indicated in Figs. 46 and 47, the lever 186 is raised by the spring 201, freeing the stop lever 198, which is returned by the spring 199 into the path of the projection 197 of the clutch. This stops the rotation of the shaft 22^a while the "rebound" at the same time is prevented by the hook 202. Simultaneously with this releasing action of the clutch the lever 186 in its upward movement forces the rod 184^a forward. The spring 181 and the contact collar 184 then return the work guard to its initial position.

When the machine is at rest the carrier 15 is in its lowest position with the looper fingers below the plane of the cord feeding needle, the needles have been advanced and given a quarter turn, and the looper fingers have been retracted forming the loops so that the work may be readily applied to the needles.

The operation of the machine will be readily understood by those skilled in the art from the description previously given, and a separate description thereof is considered unnecessary.

It is usually not necessary to adjust the spacings of the looper fingers, and whenever it is desired so to do it may be accomplished by shifting them independently, as has been previously described. In Figs. 50 and 51, however, means are shown for simultaneously moving these looper fingers in a manner similar to that set forth in connection with the needles. The projection 64 of the holder 65, instead of being adapted to receive binding screws, may be solid and extended through the slot in the plate 53. Above the plate each projection 64 is piv-

oted to a lever 213, fulcrumed upon the upper side of the plate 53. Each lever 213 carries a cam roll 214 arranged in a curved slot 215 in an adjusting lever 216 fulcrumed at some convenient point upon the plate 53, 70 and having an operating arm 217. The levers 213 and the slots 215 in the operating lever 216 are so arranged that by shifting said lever 216 a movement is imparted to the levers 213, which will give the looper fingers 75 the desired spacings, and maintain the adjustment so made.

In Fig. 53 is shown a simple and efficient means for longitudinally adjusting the needles to bring them into the precise position 80 desired. In this figure 400 represents a lever pivoted on the shaft 12. The upper end of this lever carries a roll 45 arranged in the cam slot 46 in the cam 53. 403 represents an adjusting screw arranged in the 85 lever 13, the end of said screw being tapped into the end of the lever 400 above the roll 45. 402 represents a screw arranged in the lever 13 and adapted to engage the lever 400 below the screw 403. By turning the screws 90 402 and 403 the lever 13 can be adjusted toward and away from the lever 400 to adjust the needles in or out, as desired.

The invention having been thus described what is claimed is:

1. A machine for lacing shoe uppers, having, in combination, a plurality of needles each of which is provided with an eye opening on the side of the needle to receive a lacing cord, means for engaging the lacing cord in the eyes of the needles while the needles are out of engagement with the work and means cooperating with the needles to form a series of loops in the cord and retain the loops in position to be passed by the 105 needles through the eyelet holes of an upper.

2. A machine for lacing shoe uppers, having, in combination, a plurality of needles arranged to pass a series of loops of lacing cord through the eyelet holes of an upper, 110 each of said needles being provided with an eye opening on the side of the needle to receive the lacing cord, means for feeding a lacing cord at one side of the needles, and means for moving the needles laterally to 115 engage the cord.

3. A machine for lacing shoe uppers, having, in combination, a plurality of needles arranged to pass a series of loops of lacing cord through the eyelet holes of an upper, 120 each of said needles being provided with an eye opening on the side of the needle to receive the lacing cord, and means for relatively moving the cord and needles to engage the lacing cord in the eyes of the 125 needles while the needles are out of engagement with the work.

4. A machine for lacing shoe uppers, having, in combination, means for passing loops of lacing cord through the eyelet holes of 130

an upper, means for presenting the lacing cord to said means, means for holding the free end of the cord, and means acting on the cord adjacent said holding means to draw cord from the supply prior to the formation of the loops.

5. A machine for lacing shoe uppers, having, in combination, a plurality of needles, means coöperating therewith to form a series 10 of loops in a lacing cord and retain the loops in position to be passed by the needles through the eyelet holes of an upper, means for feeding the lacing cord to the needles, and means acting on the cord at one side 15 of the needles to draw cord from the supply prior to the formation of the loops.

6. A machine for lacing shoe uppers, having, in combination, a plurality of needles, means coöperating therewith to form a series 20 of loops in a lacing cord and retain the loops in position to be passed by the needles through the eyelet holes of an upper, means for feeding the lacing cord to the needles, means for holding the free end of the cord, 25 and means acting on the cord between the needles and said holding means to draw cord from the supply prior to the formation of the loops.

7. A machine for lacing shoe uppers, having, in combination, a plurality of needles arranged to pass a series of loops of lacing 30 cord through the eyelet holes of an upper and means for simultaneously adjusting said needles to space the needles in accordance 35 with the spacing of the eyelet holes in the upper to be laced.

8. A machine for lacing shoe uppers, having, in combination, a plurality of needles arranged to pass a series of loops of lacing 40 cord through the eyelet holes of an upper and adjusting mechanism acting when actuated to change the relative lateral position of the needles to space the needles in accordance with the spacing of the eyelet holes 45 in the upper to be laced.

9. A machine for lacing shoe uppers, having, in combination, a plurality of needles arranged to pass a series of loops of lacing 50 cord through the eyelet holes of an upper and an adjusting lever and suitable connections for changing the relative lateral positions of the needles to space the needles in accordance with the spacing of the eyelet holes in the upper to be laced.

55 10. A machine for lacing shoe uppers, having, in combination, a plurality of needles, means coöperating therewith to form a series of loops in a lacing cord and retain the loops in position to be passed by the 60 needles through the eyelet holes of an upper, and means for simultaneously adjusting the length of a plurality of said loops.

11. A machine for lacing shoe uppers, having, in combination, a plurality of needles, a plurality of looper fingers coöperat- 65

ing therewith to form a series of loops in a lacing cord and retain the loops in position to be passed by the needles through the eyelet holes of an upper, and an adjusting mechanism common to all of the looper fingers for adjusting said looper fingers to vary the length of the loops.

12. A machine for lacing shoe uppers, having, in combination, a plurality of needles, a plurality of looper fingers coöperating therewith to form a series of loops in a lacing cord and retain the loops in position to be passed by the needles through the eyelet holes of an upper, and means for simultaneously adjusting a plurality of said 70 looper fingers to vary the length of a plurality of the loops.

13. A machine for lacing shoe uppers, having, in combination, means including a plurality of needles for forming loops in a lacing cord and for passing said loops through the eyelet holes of an upper and means for simultaneously adjusting the 85 length of a plurality of said loops to vary the amount of slack in the completed lacing.

14. A machine for lacing shoe uppers, having, in combination, a plurality of needles, means coöperating therewith to form a series of loops in a lacing cord and retain the loops in position to be passed by the needles through the eyelet holes of an upper, means for passing a locking cord through 95 said loops and a work guard at one side of the needles, adjustable toward and from the needles.

15. A machine for lacing shoe uppers, having, in combination, a plurality of needles, means coöperating therewith to form a series of loops in a lacing cord and retain the loops in position to be passed by the 105 needles through the eyelet holes of an upper, a cord feeding needle arranged to pass a locking cord through said loops and a work guard on the same side of the needles as the cord feeding needle adjustable toward 110 and from the needles.

16. A machine for lacing shoe uppers, having, in combination, a plurality of needles arranged to pass a series of loops of lacing 115 cord through the eyelet holes of an upper, means for feeding the lacing cord to said needles, and means for simultaneously adjusting said needles longitudinally.

17. A machine for lacing shoe uppers, having, in combination, a plurality of needles, a plurality of looper fingers coöperating therewith to form a series of loops in a lacing cord and retain the loops in position to be passed by the needles through the eyelet holes of an upper, and means for simultaneously adjusting said looper fingers to space the fingers at the desired distance apart.

18. A machine for lacing shoe uppers, having, in combination, a plurality of nee- 130

cles arranged to pass a series of loops of lacing cord through the eyelet holes of an upper, a cord feeding needle arranged to feed the cord to the needles and to pass a portion 5 of the cord through said loops, and cord grippers arranged in proximity to the path of the cord feeding needle and at substantially the same distance therefrom, acting respectively to grip the free end of the cord 10 and the end of the portion of the cord passed through the loops.

19. A machine for lacing shoe uppers, having, in combination, means for passing a series of loops of lacing cord through the 15 eyelet holes of an upper, a cord feeding needle arranged to pass a locking cord through said loops, and a cutting blade against which the locking cord is drawn during the retracting stroke of the needle to 20 sever the cord.

20. A machine for lacing shoe uppers, having, in combination, means for passing a series of loops of lacing cord through the eyelet holes of an upper, a cord feeding 25 needle arranged to pass a locking cord through said loops, a cutting blade against which the cord is drawn during the retracting stroke of the needle, a tension device movable with the needle, and means for 30 actuating the tension device to engage the cord during the backward stroke of the needle.

21. A machine for lacing shoe uppers, having, in combination, means for passing a 35 series of loops of lacing cord through the eyelet holes of an upper, a cord feeding needle arranged to pass a locking cord through said loops, a cord severing device arranged to act on the locking cord during 40 the retracting stroke of the needle, a tension device movable with the needle, means for actuating the tension device to engage the cord during the backward stroke of the needle, and means for adjusting said tension 45 device for operation upon cords of different sizes.

22. A machine for lacing shoe uppers, having, in combination, means for passing a series of loops of lacing cord through the 50 eyelet holes of an upper to partially form a lacing, means for passing a portion of said cord through said loops to complete the lacing, a knot-tying mechanism arranged to act on the ends of the lacing, beyond the loops 55 and a separate knot-tightening device co-operating with the knot-tying mechanism to tighten the knot formed thereby.

23. A machine for lacing shoe uppers, having, in combination, means for passing a 60 series of loops of lacing cord through the eyelet holes of an upper to partially form a lacing, means for passing a portion of said cord through said loops to complete the lacing, a knot-tying mechanism arranged to 65 act on the ends of the lacing, a guard arm

arranged to prevent the work from interfering with the operation of the knot-tying mechanism, and a knot-tightening device co-operating with the knot-tying mechanism and guard arm to tighten the knot formed 70 by the knot-tying mechanism.

24. A machine for lacing shoe uppers, having, in combination, a plurality of needles, means co-operating therewith to form a series of loops in a lacing cord and retain 75 the loops in position to be passed by the needles through the eyelet holes of an upper, means for passing a locking cord through said loops, and a work adjusting device acting to adjust the work on the needles prior to the passage of the locking cord 80 through the loops.

25. A machine for lacing shoe uppers, having, in combination, a plurality of needles, means co-operating therewith to form a 85 series of loops in a lacing cord and retain the loops in position to be passed by the needles through the eyelet holes of an upper, means for passing a locking cord through said loops, a work adjusting device, and 90 means for moving said adjusting device across the ends of the needles and longitudinally of the needles prior to the passage of the locking cord through the loops.

26. A machine for lacing shoe uppers, 95 having, in combination, a plurality of needles, means co-operating therewith to form a series of loops in a lacing cord and retain the loops in position to be passed by the needles through the eyelet holes of an upper, 100 a stop mechanism for throwing the machine into and out of operation, a movable guard for protecting the hands of the operator from injury by the lacing devices of the machine, and connections between the guard 105 and the stop mechanism whereby the guard is moved into operative position before the stop mechanism is thrown into operation.

27. A machine for lacing shoe uppers, 110 having, in combination, a plurality of needles, means co-operating therewith to form a series of loops in a lacing cord and retain the loops in position to be passed by the needles through the eyelet holes of an upper, 115 means for passing a locking cord through said loops, a work adjusting device, a stop mechanism for throwing the machine into and out of operation and connections between the stop mechanism and the work adjusting device whereby the work adjusting device is moved across the ends of the needles and then longitudinally thereof to protect the hands of the operator and adjust the work before the machine is thrown into 120 operation.

28. A machine for lacing shoe uppers, 125 having, in combination, means for passing a series of loops of lacing cord through the eyelet holes of an upper to partially form a lacing, means for passing a portion of 130

- said cord through said loops to complete the lacing, cord grippers arranged to grasp the ends of the lacing, and a knot-tying mechanism arranged to act on the lacing adjacent the cord grippers, comprising rotatable and reciprocating jaws, a latch arranged to hold the lacing on the jaws during their rotation and to release the lacing after it has been grasped by the working faces of the jaws, and means for actuating the jaws and latch.
29. A machine for lacing shoe uppers, having, in combination, means for passing a series of loops of lacing cord through the eyelet holes of an upper to partially form a lacing, means for passing a portion of said cord through said loops to complete the lacing, cord grippers arranged to grasp the ends of the lacing, and a knot-tying mechanism arranged to act on the lacing adjacent the cord grippers, comprising rotatable and reciprocating jaws, means for retaining the lacing on the jaws during their rotation, a thread arm arranged to place the lacing between the working faces of said jaws, and means for actuating the jaws and thread arm.
30. A machine for lacing shoe uppers, having, in combination, means for passing a series of loops of lacing cord through the eyelet holes of an upper to partially form a lacing, means for passing a portion of said cord through said loops to complete the lacing, cord grippers arranged to grasp the ends of the lacing, a knot-tying mechanism arranged to act on the lacing adjacent the cord grippers, comprising rotatable and reciprocating jaws, one of which is provided with a guiding groove for the lacing and the other of which is provided with an inclined shoulder to deflect the lacing during the rotation of the jaws, and means for actuating the jaws.
31. A machine for lacing shoe uppers, having, in combination, means for passing a series of loops of lacing cord through the eyelet holes of an upper to partially form a lacing means for passing a portion of said cord through said loops to complete the lacing, cord grippers arranged to grasp the ends of the lacing, a knot-tying mechanism arranged to act on the lacing adjacent the cord grippers, comprising rotatable and reciprocating jaws, one of which is provided with a guiding groove for the lacing, and the other with a deflecting shoulder, a latch arranged to retain the lacing on the jaws during their rotation and to release the lacing after it has been placed between the working faces of the jaws, and means for actuating the jaws and latch.
32. A machine for lacing shoe uppers, having, in combination, a plurality of needles arranged to pass a series of loops through the eyelet holes of an upper to partially form a lacing, means for passing a portion of said cord through said loops to complete the lacing, cord grippers arranged to grasp the
- partially form a lacing, means for passing a portion of said cord through said loops to complete the lacing, cord grippers arranged to grasp the ends of the lacing, a knot-tying mechanism arranged to act on the lacing adjacent the cord grippers, comprising rotatable and reciprocating jaws, a thread finger, and means for actuating the thread finger to draw cord from the supply prior to the formation of the loops and to place the lacing in the jaws of the knot-tying mechanism.
33. A machine for lacing shoe uppers, having, in combination, a plurality of needles, means coöperating therewith to form a series of loops in a lacing cord and retain the loops in position to be passed by the needles through the eyelet holes of an upper, means for feeding a lacing cord in proximity to the needles, and means for moving the needles laterally to engage the lacing cord prior to the operation of the means co-operating with the needles to form the lacing cord into loops.
34. A machine for lacing shoe uppers, having, in combination, a plurality of needles, means coöperating therewith to form a series of loops in a lacing cord and retain the loops in position to be passed by the needles through the eyelet holes of an upper, a cord-feeding needle arranged to feed the lacing cord in proximity to the needles and to pass a portion of the cord through the loops after they have been passed through the eyelet holes of the upper, means for moving the needles laterally to engage the lacing cord, to bring the needles into a convenient position to pass the loops of lacing cord through the eyelet holes of the upper, and to bring the loops into line with the cord-feeding needle.
35. A machine for lacing shoe uppers, having, in combination, a plurality of needles, arranged to pass a series of loops of lacing cord through the eyelet holes of an upper, each of said needles being provided with an eye opening on the side of the needle to receive the lacing cord, means for feeding a lacing cord at one side of the needles, means for relatively moving the cord and needles to engage the cord in the eyes of all of the needles before any loop is passed through the eyelet holes, means for moving the needles longitudinally to seat the cord in the eyes of the needles, and means for passing a locking cord through the loops of lacing cord after said loops have been passed through the eyelet holes of the upper.
36. A machine for lacing shoe uppers, having, in combination, means for passing a series of loops of lacing cord through the eyelet holes of an upper to partially form a lacing, means for passing a portion of said cord through said loops to complete the lacing, cord grippers arranged to grasp the

ends of the lacing, a knot-tying mechanism arranged to act on the lacing adjacent the cord grippers, a thread arm and means for actuating said arm to draw the ends of the lacing from the cord grippers.

37. A machine for lacing shoe uppers, having, in combination, means for passing a series of loops of lacing cord through the eyelet holes of an upper to partially form a lacing, means for passing a portion of said cord through said loops to complete the lacing, cord grippers arranged to grasp the ends of the lacing, a knot-tying mechanism arranged to act on the lacing adjacent the cord grippers comprising rotatable and reciprocating jaws; a thread arm and means for actuating the arm to place the lacing in the jaws of the knot-tying mechanism and to draw the ends of the lacing from the cord grippers.

38. A machine for lacing shoe uppers, having, in combination, a plurality of needles, means coöperating therewith to form a series of loops in the lacing cord, a stop mechanism for throwing the machine into and out of operation, a work adjuster for positioning the work upon the needles, means for operating the work adjuster to engage the work and for operating the stop mechanism to start the machine, and mechanism for automatically disengaging the work adjuster from the work and resetting the stop mechanism.

39. A machine for lacing shoe uppers, having, in combination, a plurality of needles, means coöperating therewith to form a

series of loops in the lacing cord, a stop mechanism for throwing the machine into and out of operation, a work adjuster for positioning the work on the needles, connections between the work adjuster and stop mechanism whereby the work adjuster is moved into work engaging position before the stop mechanism is thrown into operation, means for manually operating the work adjuster to engage the work, and means for automatically disengaging the work adjuster from the work and setting the stop mechanism to stop the machine.

40. A machine for lacing shoe uppers, having, in combination, a plurality of needles, means coöperating therewith to form a series of loops in the lacing cord, a work adjuster for positioning the work on the needles, a stop mechanism for throwing the machine into and out of operation, an actuator rod and connections for actuating the work adjuster to engage the work and for thereafter actuating the stop mechanism to start the machine, mechanism for automatically disengaging the work adjuster and stop mechanism from the actuator rod and for disengaging the work adjuster from the work and resetting the stop mechanism to stop the machine.

In testimony whereof I have affixed my signature, in presence of two witnesses.

WILLARD A. SMITH.
